DR D 16.833

D16 833

UNITED STATES PATENT OFFICE.

JULIUS PEGEL, OF CAMDEN, NEW JERSEY, ASSIGNOR TO JOHN BROMLEY & SONS, OF PHILADELPHIA, PENNSYLVANIA.

DESIGN FOR A RUG.

SPECIFICATION forming part of Design No. 16,833, dated August 3, 1886.

Application filed June 19, 1886. Serial No. 205,729. Term of patent 34 years.

To all whom it may concern:

Be it known that I, JULIUS PEGEL, a subject of the Emperor of Germany, and a resident of Camden, New Jersey, have invented and produced a new and original Design for Rugs, of which the following is a specification, reference being had to the accompanying photographic illustration, to which reference is made.

10 In the illustration, A is a continuous rectangular border formed of clusters of leaves and flowers in a continuous line. Part of the space at each end, within the border, is inclosed by the double scrolls B B, forming panels, and 15 each of these panels is ornamented by leaves C and fancy flowers D. The middle space is ornamented by a large cluster of large and small leaves E E and fancy flowers F F.

20 The leading features of my design will be apparent from the claim.

In the photographic illustration I have omitted from one end of the design the part outside the vertical scroll at that end, as it would be a mere duplication of what is shown outside of the vertical scroll at the other end. 25

What I claim is—

A design for rugs, consisting of the continuous border A, formed of leaves and flowers, double scrolls B B, forming end panels, with flower and leaf ornamentation, and the central ornamentation, consisting of a large cluster of leaves, E E, and fancy flowers F F, substantially as shown and described. 30

JULIUS PEGEL.
